UNITED STATES PATENT OFFICE.

CARL S. BATES, OF CHICAGO, ILLINOIS, ASSIGNOR TO LINCOLN RADIO CORPORATION,
OF CHICAGO, ILLINOIS, A CORPORATION OF ILLINOIS.

DESIGN FOR A RADIOANTENNA.

Application filed December 18, 1925. Serial No. 15,784. Term of patent 14 years.

To all whom it may concern:

Be it known that I, CARL S. BATES, a citizen of the United States, residing at Chicago, in the county of Cook and State of Illinois, have invented a new, original, and ornamental Design for Radioantenna, of which the following is a specification, reference being had to the accompanying drawing, forming part thereof.

The figure is a perspective view of a radio antenna showing my new design.

I claim:

The ornamental design for a radioantenna, as shown.

In witness whereof, I hereunto subscribe my name this 10 day of December, 1925.

CARL S. BATES.
